UNITED STATES PATENT OFFICE.

JOHN A. FINCKE, OF NEW YORK, N. Y.

WATERPROOF CEMENT BLOCKS.

Specification of Letters Patent. Patented Sept. 14, 1909.

934,061.

Application filed March 13, 1908. Serial No. 420,966.

To all whom it may concern:

Be it known that I, JOHN ALBERT FINCKE, a citizen of the United States, residing at 30 Beekman Place, in the borough of Manhattan, city of New York, and county and State of New York, have invented new and useful Improvements in Waterproof Cement Blocks and in the Manner of Applying the Same, particularly in constructing what is known as "Portland-cement stucco structures," of which the following is a full, clear, and exact specification, reference being had to the accompanying drawings, wherein—

Figure 1 is a sectional view, on a vertical line, and Fig. 2 a similar view on a horizontal line, showing the construction of such blocks and the joints between them; Fig. 3 is an isometric view of a clamp employed for fastening together the adjoining blocks in such structure; Fig. 4 a similar view of my improved cement blocks, showing the grooves and recesses for the insertion of the clamp to fasten together two adjoining blocks; Fig. 5 is an isometric view of such a block and of the anchor for securing it to the frame-work of the structure; Fig. 6 is a similar view showing such an anchor apart from the block in reversed position to that shown in Fig. 5; and Fig. 7 is an isometric view of a portion of a structure, showing my improved cement blocks applied to the exterior surface of a building.

The blocks A consist of a body or core b; a water-proof cement veneer a, and of a bituminous backing c. The core b is made of ordinary hydraulic cement and sand, formed in plastic state and reinforced by metal lath of any suitable character. In forming the core, the metal lath is embedded in the plastic mass in the usual manner while in the mold, to form a stiffening or reinforcing core for the body thereof. The veneer a is composed of a water-proof mixture of Portland cement and sand with the addition of a suitable proportion of silicate of soda and any coloring matter as may be desired. By using with the cement, a small proportion of finely ground, burnt clay, a water-proof veneer resembling closely terra cotta, both in color and in appearance, is produced. This veneer a is preferably united with the body or core b of the block in the process of its manufacture. This may be done by spreading the material for the veneer on the bottom of the mold and then applying thereon the cement and sand grout, used for casting

the body b; it is, however, equally feasible to produce the veneer by applying the materials recited on the top of the body or core b when formed in the mold. It must, of course, be understood that in either way of manufacture the veneer a must be joined to the body or core b before the grout or cement mixture has set. The outer surface of the veneer a may be finished in any desired manner.

The bituminous backing c is applied after the veneer a and core b of the block have set. This is done by immersing the block in a vessel, containing molten bitumen, to a depth corresponding to the thickness of the body or core b, holding the veneered face thereof on top. Before such immersion, the block should be heated to about 140 to 175° F. The immersing of the blocks is preferably done in an open and adequately deep vessel containing a larger quantity of the molten bitumen and provided with suitable arrangement, to prevent immersing of the blocks too deeply. In such deeper vessel the bitumen can be kept in a constantly molten state, by heating the bottom of the vessel and the blocks may be handled more easily and without danger of soiling or defacing their veneered surfaces.

To produce the backing more substantially, when it is desired, the back of the core b may be roughened with a suitable implement, or a suitable medium, in the form of wire gauze, or the like, for holding the bitumen, may be applied thereon. This addition, however, need be resorted to only in exceptional cases. For ordinary purposes, it will be found amply sufficient to produce the backing c by merely immersing the blocks when set, dried and heated in the molten bitumen as above explained.

As will be seen with reference to Figs. 1, 2, 4 and 5, the core b of each block is provided with corresponding grooves and tongues g and g', so that when the blocks are joined together, the tongue of one enters the corresponding groove of the other. The backing c of the bituminous material extends to the sides of the core b, as shown in Figs. 1 and 2, and therefore, in forming the grooves g and the tongues g', this circumstance must be taken in consideration and the tongues g' be made correspondingly smaller, and the grooves g correspondingly larger, to permit snug joining of the blocks together.

The horizontally adjoining blocks are fastened together by clamps j , such as shown in Fig. 3, and for this purpose, recesses j' , formed in the tongues g' , and grooves j^2 5 are provided, the grooves j^2 extending from the recesses j' to the edge of each block, to permit embedding therein of the clamps j , as shown in sectional view in Fig. 1.

For securing the blocks to the frame-work 10 of the structures such anchors as shown in Fig. 6 are employed. They consist of a hook-shaped point t , and a shank t' . The hook t is formed to embrace the tongue g' of the block, and suitable recess is provided 15 in the groove g of the block and in the adjoining flange, to receive the anchor. Shanks t' are provided with suitable perforations t^2 for affixing them to the framework of the structure and may also be provided with points t^3 for securing them in 20 place. As shown in Figs. 6 and 7, these anchors are preferably applied on the ends of the blocks where they are joined together with the clamps j . The object of this is to 25 add to the rigidity of the structure and also to give the anchor a safer and stronger hold upon the block.

The blocks may be formed in any desirable sizes and shapes, with even or ornamental surfaces, as shown in Figs. 1 and 7, and after they have been joined together 30 and to the structure, the face joints between the blocks are preferably pointed up with the same composition as is used for the

veneers a of the blocks, thus producing a uniform appearance of the surface of the building.

I claim as my invention:

1. A water-proof cement block, consisting of a core of hydraulic cement and sand grout, a veneer of water-proof cement composition on one face, and of a backing of bituminous material on the other face thereof, substantially as herein shown and described. 4

2. A stucco structure of water-proof cement blocks, consisting of a core of hydraulic cement and sand grout, a veneer of water-proof cement composition on one face, and of a backing of bituminous material on the other face thereof; means for joining the blocks together and for affixing them to the frame-work of the building, substantially as herein shown and described. 50

3. A facing of a building, flooring or ceiling, of water-proof cement blocks, consisting of a core of hydraulic cement and sand grout, a veneer of water-proof cement composition on one face, and of a backing of bituminous material on the other face thereof, secured together by clamps and to the frame-work of the building by anchors, substantially as herein shown and described. 55 60

JOHN A. FINCKE.
